UNITED STATES PATENT OFFICE.

CHARLES VALENTIN FERDINAND LUDWIG, OF ST. LOUIS, MISSOURI.

FILTERING APPARATUS.

SPECIFICATION forming part of Letters Patent No. 625,177, dated May 16, 1899.

Application filed April 21, 1898. Renewed April 22, 1899. Serial No. 714,100. (No model.)

To all whom it may concern:

Be it known that I, CHARLES VALENTIN FERDINAND LUDWIG, of St. Louis, in the State of Missouri, having invented a new and Improved Filtering Apparatus, of which the following is a full, clear, and exact description.

The object of the invention is to provide a new and improved filtering apparatus more especially designed for obtaining pure water from rivers, streams, and other sources of water-supply, the apparatus being arranged to filter the water directly and return the sediment to the source of supply.

The invention consists of novel features and parts and combinations of the same, as will be described hereinafter and then pointed out in the claims.

Reference is to be had to the accompanying drawings, forming a part of this specification, in which similar characters of reference indicate corresponding parts in all the figures.

Figure 1 is a sectional side elevation of the improvement. Fig. 2 is an enlarged plan view of the filter-bed with parts in section, and Fig. 3 is a sectional side elevation of the same on the line 3 3 of Fig. 2.

The improved apparatus illustrated in the drawings is more especially designed for use in a river, and for this purpose an abutment A is arranged on the shore of the river, and a second abutment A' is arranged parallel to the abutment A and extends in the direction of the flow of the river, so that the water-current can readily pass between the two abutments. A filter B is immersed in the water between the abutments and is hung on ropes, chains, or like devices C, extending upwardly and passing over pulleys C', journaled in suitable bearings in a framework D, carried by the abutments A A'. Counterweights C² are hung on the ends of the ropes C to counterbalance the filter B, so that the latter automatically rises and falls with the water in the river, to be at all times immersed a desired distance. The filter B is in the form of a box open at the top and provided near the lower ends of its sides, as well as at the bottom B², with apertures for the water to pass into an entrance-chamber E, arranged in the lower end of the box.

The chamber E is guarded at the front end E' by projecting this part in triangular form

beyond the filter B, the triangular end extending into the current to deflect refuse or other floating matter, at the same time permitting of the current to pass into the chamber with full force. A filter-bed is arranged above the entrance-chamber, but not above the front end thereof, and this bed consists of a substantial frame or bottom F, having fenestrated openings or spaces into which are fitted semitubular porous plates F', made of artificial stone, tripoli, brick, tile, or other similar material, on the top of which is arranged one or more strata of gravel, sand, or like material G, above which is formed a reservoir H, into which the filtered water accumulates. Now it is evident that when the filter B is immersed in the water the latter passes through the filter-bed in an upward direction into the reservoir H by the pressure of the water in the river—that is, until the level of the filtered water in the reservoir H corresponds to the level of the water in the river.

Now it is evident that by the arrangement described the filter B is sufficiently far immersed in the water in the river that the middle stratum of the water is approximately at the entrance-chamber E, so that the lighter polluting-matter which floats on the surface of the river-water and the heavier substances which move along the bed of the river are not liable to enter the filter. The water passing into the entrance-chamber E is thus comparatively pure and is perfectly free of all impurities before passing into the reservoir H, as sediment is prevented from passing into the said reservoir by the bottom F' and the filtering-strata G.

In order to sterilize and purify the water in the reservoir H, I provide opposite sides of the box B' with carbon plates I I', connected by wires J J' with a dynamo at a suitable distant station K, so that a current of electricity passes through the water in the reservoir H to sterilize and purify the same. The filtered, sterilized, and purified water flows from the upper portion of the reservoir H, through pipes L, into a flexible pipe L', connected with a pipe L², arranged in the abutment A, and discharging in a cistern or other water-collecting vessel N, arranged on the

shore, the vessel N being located sufficiently low in the ground for the water to flow by its own gravity from the reservoir H to the said cistern. A pipe O connects the bottom of the 5 cistern with the station K, containing pumps or the like for pumping the water to a reservoir or directly to city mains for distribution.

In order to keep the bottom F' as clean as possible from the rough sediment liable to 10 collect upon the under surface of said bottom F' in the pores of said bottom, I form the latter with longitudinally-extending arches F', each containing a brush P, having its shaft P' journaled in suitable bearings in the ends of the box B'. On the ends of each shaft P' are secured propeller-wheels P², extending directly into the water-current of the river, so that the propeller-wheels are turned, and consequently the brushes P are rotated, to scrape 15 off any sediment passing to the under surface of the arches F'. The sediment thus removed readily floats off or settles in the bottom of the river, and the bottom F' is kept comparatively free from impurities for a long time.

20 25 When it is deemed necessary to clean the filter B, the latter may be easily hoisted out of the water by increasing the counterweights C² or by pulling on the ropes C.

The filter-bed, composed of the bottom F 30 and the strata G of sand, gravel, and the like, can be readily renewed whenever desired and without incurring very much expense.

I do not limit myself to the particular construction of the abutments and the filter B as 35 described, as it is evident the filter may be suspended between twin boats or supported from docks or otherwise floated in the river to rise and fall with the water therein for the purpose mentioned; or in the event of water 40 not having force of current sufficient to rotate propeller-wheels other mechanical motive power may be applied for the purpose mentioned.

Having thus fully described my invention, 45 I claim as new and desire to secure by Letters Patent—

1. A filter having a filtering-wall construct-

ed with arches, and revolute brushes in contact with the arch-surfaces.

2. A filter having a filtering-wall constructed with arches, revolute brushes in contact with the arch-surfaces, and propellers operatively connected with the brushes and arranged to be actuated by the current.

3. A filtering apparatus, provided with a filter held in the source of water-supply and provided in its lower portion with inlets for the water, a filter-bed in said filter above the inlets, a collecting-reservoir in said filter above the bed, so that the water from the 60 source of supply is forced up through the filter-bed into the reservoir by the pressure of the water from the source of supply, the filter-bed comprising a stone, brick, tile or like porous material bottom, and a loose filtering material on said bottom, substantially as shown and described.

4. A filter arranged for immersion in running water, and provided with revolute cleaning-brushes, and propellers operatively connected with the brushes and arranged to be actuated by the current.

5. A filtering apparatus provided with a filter arranged for immersion in the source of water-supply, and having a bottom made of a 75 solid but porous material and formed with arches, and revolute brushes in contact with the arch-surfaces, to keep the same clean and free of sediment, substantially as shown and described.

6. A filtering apparatus provided with a filter arranged for immersion in the source of water-supply, and having a bottom made of solid but porous material and formed with arches, revolute brushes in contact with the 85 arch-surfaces, to keep the same clean and free of sediment, and propeller-wheels on the shafts of the said brushes, for rotating the same by the current of water, substantially as shown and described.

CHARLES VALENTIN FERDINAND LUDWIG.
